UNITED STATES PATENT OFFICE

136,622

DESIGN FOR A PUZZLE

Fay P. Davis, Omak, Wash.

Application July 20, 1943, Serial No. 110,711

Term of patent 14 years

To all whom it may concern:

Be it known that I, Fay P. Davis, a citizen of the United States, residing at Omak, in the county of Okanogan and State of Washington, have invented a new, original, and ornamental Design for a Puzzle, of which the following is a specification, reference being had to the accompanying drawing, forming part thereof.

Figure 1 is a plan view of a puzzle showing my new design, and

Figure 2 is a side elevational view thereof.

I claim:

The ornamental design for a puzzle, as shown.

FAY P. DAVIS.
